UNITED STATES PATENT OFFICE.

ARTHUR ROSENTHAL, OF GRAND RAPIDS, MICHIGAN, ASSIGNOR TO THE ROSE LABEL MACHINE CO., OF GRAND RAPIDS, MICHIGAN.

SEWING-MACHINE FOR SPECIAL WORK.

1,199,821.

Specification of Letters Patent.

Patented Oct. 3, 1916.

Application filed December 12, 1912. Serial No. 736,258.

To all whom it may concern:

Be it known that I, ARTHUR ROSENTHAL, a citizen of the United States, residing at Grand Rapids, Michigan, have invented 5 certain new and useful Improvements in Sewing-Machines for Special Work, of which the following is a specification.

This invention relates to improvements in sewing machines for special work.

10 It relates especially to improved label attaching machines or machines for the attachment of patches or pockets for any purpose, or for stitching in similar form for reinforcement or ornamentation.

15 The invention may be incorporated into a sewing machine when it is first constructed, or it may be provided as an attachment.

The objects of this invention are, First, to provide certain improvements for use in 20 connection with the improved guiding means devised and invented by Michael Petrocchi, appearing in his patent application filed December 12, 1912, Serial No. 736,257. Second, to provide such a special

25 work structure which is effectively incased and guarded. Third, to provide an improved arrangement and connection of ratchet means for actuating the same. Fourth, to provide in a machine of this kind

30 improved means of elevating the presser foot or work holder which in no way interferes with the feed of the machine when it is at work. Fifth, to provide in such a structure, an improved automatic stop means that 35 will insure the stopping of the machine when the work is completed with the needle also in the elevated position. Sixth, to provide automatic means of insuring complete actuation of the stitching operation. Sev-

40 enth, to provide improved means of automatically associating the starting and stopping devices whereby perfect work is insured. Eighth, to provide means of insuring the complete release of all actuating

45 and tension means when the machine is stopped. Ninth, to provide improved interlocking means to avoid accidental release of, or manipulation of parts while the machine is at work.

50 Further objects, and objects relating to mere details of construction and operation will definitely appear from the detailed description to follow.

I accomplish the objects of my invention by the devices and means described in the 55 following specification.

The invention is clearly defined and pointed out in the claims.

A structure constituting a preferred embodiment of my invention is fully illustrated 60 in the accompanying drawing, forming a part of this specification, in which:

Figure I is a side perspective view of a sewing machine embodying the features of my invention. Fig. II is also a side perspective view of such a structure from the opposite side of the sewing machine. Fig. III is an inverted plan view of a sewing machine showing the driving gear therefor and the improved ratchet driving means for 70 the feed. Fig. IV is a sectional plan view of the machine, taken on a line corresponding to line 4—4 of Fig. I, the cover of the guide means being removed. Fig. V is an enlarged detail longitudinal sectional elevation view through the improved guide means, taken on a line corresponding to line 5—5 of Figs. III and IV. Fig. VI is a detail perspective view of the internal intermediate guide block of the guide mechanism. 80 Fig. VII is a detail view of the release levers, showing the relation of the same to the trip finger of the automatic stop of the sewing machine. Fig. VIII is a detail rear elevation view, in full size, of the release levers 85 and trip finger and adjacent parts, showing the relations of the same, a portion being sectioned to show details of the spring pressed pins that force the release levers normally out. Fig. IX is an inverted detail 90 perspective view of the bent stop lever actuated by the carrier head. Fig. X is a detail perspective view of the closure slides for closing the case of the guide mechanism, as they appear in perspective when removed 95 from the slideways. Fig. XI is an enlarged detail sectional view through the adjustable elevating hook, taken on a line corresponding to the line 11—11 of Fig. II, for raising the work holder or presser foot. Fig. XII 100 is a full size detail view of the parts constituting the ratchet means, showing the relation of the same, with the retaining disk removed. Fig. XIII is a detail perspective view of the detent pawl. Fig. XIV is an 105 inverted perspective view of the actuating

pawl. Fig. XV is a detail view of the retaining disk 12. Fig. XVI is an enlarged detail sectional view on line 16—16' of Fig. IV, showing the automatic interlocking 5 means.

In the drawing, all of the sectional views are taken looking in the direction of the little arrows at the ends of the section lines and similar numerals of reference refer to 10 similar parts throughout the several views.

Considering the numbered parts of the drawing, the base 1, arm 2 and head 3 of the sewing machine are of the usual form of such machine, and there is provided a suitable work plate 4. On the base plate is disposed 15 the improved guide and actuating means for the carrying head 19 which carries the feed arm 6, on which is suitably hinged the presser arm 7, by the pivots 8, 20 (see Fig. IV), carrying the work holder or presser foot 10, a tension spring 9* being provided to hold the same down yieldingly in position.

A friction ratchet wheel 11 is disposed 25 underneath the machine to drive the pinion for driving the carrying head, the same being provided with the detent pawl 13 held in position by the spring pressed pin 13' on the screw 13''. The actuating pawl 14 is operated by the link 15 which is held under tension by the spring 15' and is connected to the pivoted arm 33 which is actuated by the pitman or link 32 connected to an arm on the rock shaft 31 driven by suitable connections 30 to working parts of the sewing machine, as clearly appears in detail in Fig. III. The vertical shaft 20, which carries and is driven by the ratchet wheel 11, extends upwardly through the base guide plate 9 and carries 35 the pinion 28 which meshes with the side 29 and end 30 of the internal rack of the carrier head 19, as clearly appears in Figs. IV and V.

The carrier head 19 is provided with 40 downwardly projecting flanges 19* disposed in rectangular relation, and rests upon the intermediate guide block 27 which is provided with guide ribs 25 on its under side adapted to travel in the guideways 24 in the 45 said base plate 5. These parts are slotted and disposed to act in precisely the same manner as the parts bearing similar numbers appearing in the patent application of Michael Petrocchi above referred to where 50 they are described in detail.

A connection 16 to be operated by the foot or otherwise, is provided for operating the lifter for the presser foot or work holder; and for releasing the sewing machine tension. A lever 54 is fulcrumed at 55 on the side of the arm of the machine, (see Fig. II), and is actuated by slotted lever 53 which is acted on by the link 52 by the connection 16. A downwardly-projecting arm 65 56, terminating in a suitable enlargement or

head, carries a depending hook 58 which is pivoted at 57, and is held yieldingly downward by the spring pressed pin 60 against the projecting finger 59. The position of the said hook is adjustable by the set screw 70 61, and the yielding pin 60 permits the hook when it engages the opposed hook 17, to swing into more secure engagement as the parts are elevated. An upwardly projecting rigid hook 17 is secured to the hinged arm 7 and projects upwardly in position to engage the hook 58, when the work holder has completed its evolution, whereby, when the connection 16 is pulled, the hinged arm 7 will be raised because the hook 58 is in position to engage the hook 17, and owing to the pivoted relation of the said hook 58 and the yielding connection, the same is very securely engaged, although its tendency otherwise would be to swing out of engagement. 85

The forward end of arm 54 is connected at 54' to the thread tension release means which is carried by the sewing machine head.

Underneath the carrier arm 6 is secured 80 a guard 62 by a horizontal flange 62', which is upwardly curved at each end to protect the lubricated parts of the carrier head.

The space about the arm 6 is effectively closed and the access of dust or dirt to the carrier head and guides is prevented by a series of slides 26, 26', 26'', slotted to conform to the said arm 6 and disposed in a transverse guide slot, as clearly appears in Figs. IV and V. The separated parts and their 100 relations to each other clearly appear in Fig. V and the separated parts in Fig. X.

I provide an automatic trip means that cooperates with the usual stop for such sewing machine, to insure the stopping of the machine automatically when the work is completed with the needle in the elevated position, so that the presser foot can be immediately raised and the completed work removed and new work inserted. To this end 110 I pivot the bent lever 35 within the casing for the carrier head, pivoting the same at 35' and providing a pin 36 on its under surface, which cooperates with the pin 37 on the top of the carrier head, whereby, when the carrier head reaches the point of completion, the lever 35 will be pushed outward to cooperate with a release lever pivoted on the base of the machine. A pair of these release levers is fulcrumed on the vertical pivot 40. 115 The release lever 38 has an upwardly-projecting stop portion 39 to cooperate with the end of the bent lever 35, and is provided with a beveled catch 41, as seen in Fig. VIII, and at the right of Figs. I and IV. These release 125 levers engage the trip finger 46 which is carried on and rocks the shaft 63 for operating the clutch and brake mechanism 51 usually provided on sewing machines of this kind. The usual automatic release lever 43, also 130

fulcrumed at 40, is provided to coöperate with the said trip finger, to insure its release at such time as to stop the machine with the needle in the elevated position. The parts 5 to secure the stopping of the needle in the elevated position are in common use on sewing machines. I do not describe the same in detail.

The lower lever 43 is constantly reciprocated by means of the arm 49 which may be actuated by means of the shuttle or needle driving rockshaft and is out of engagement with the trip finger 46 when the needle is in the elevated position. Thus when the lever 15 38 is actuated to release the trip finger, if the needle is in the elevated position at that time, it will notwithstanding force the lever 43 out of engagement with the trip finger, and said trip finger 46 will be completely released and the stop mechanism actuated.

The rear end of the lever 38 is extended laterally and bent upwardly at 42, and the lower lever 43 is correspondingly bent downwardly at 45 and these two parts rest yieldingly against spring pins 47 in the block 48, the spring pressed pins 47 being provided to hold the same normally outward but yieldingly in position. The arm 49 which may be actuated by the shuttle or feed rock shaft 30 constantly reciprocates the lower lever 43 to insure the release of the trip at the proper time, as before indicated. The trip finger 46 is secured by a set screw to rock shaft 63.

In order to insure the complete and effective operation of my machine, I provide an interlocking device. This is operated from the transverse trip finger rock shaft 63 associated with the automatic stop means at the right of the machine. On this shaft 63 is an arm or finger 64, which coöperates with the interlocking plunger 65, which is beveled at 65', (see Fig. XVI) and guided in suitable perforated lugs or brackets 67, (see Figs. II, IV and XVI). The plunger 65 is held normally disengaged by a suitable spring. This is preferably a coiled spring 68 connected at one end to the plunger and at the opposite end to one of the brackets 67, the same being preferably an extension spring which withdraws the plunger.

The rear end of the plunger, (see Figs. II and IV) is acted upon by the finger 64. The connections 16 for raising the presser foot, (see Figs. II, IV and XVI) is perforated transversely at 66 in line with the beveled end 65' of the plunger 65, when in its upper position. Because the plunger 65 is beveled at 65' on its upper side, it enters this aperture with a wedging action, and therefore forces the connection to its uppermost position. Because it is acted upon by the finger 64 on the shaft 63, it is impossible to swing the trip finger 46 to the locking position without the connection 16 is at its highest point to permit the plunger 65 being de-

pressed by the finger 64. When the trip finger 46 is engaged by the release levers, it is therefore impossible, because of the engagement of the plunger 65 with the connection 16, to depress the same by the foot lever, 70 or any means, until the trip finger 46 is released. Because the trip finger 46 is released only on the completion of the work, the operative cannot prematurely raise the presser foot, and because the lever 54 is, as 75 before stated, also connected to the tension, it is only possible to release the tension and permit the withdrawal of the work after the machine is stopped. This automatic action of these various parts prevents the interference by an operative with the correct operation of the machine. A machine with these features, to use a trite expression, is substantially "fool proof".

The features of the invention can be made 85 use of with other styles of carrier head and arm and with other means for actuating the same.

Much of the apparatus can be used with 90 any sort of feed mechanism.

Various modifications will no doubt suggest themselves to those skilled in the art to which this invention pertains.

Having thus described my invention, what I claim as new and desire to secure by Letters Patent is:

1. In a special work sewing machine, the combination of a carrier head, means for guiding the same in a predetermined path, a work holder carried by the carrier head, 100 automatic stop means for said sewing machine, including a rock shaft and a trip arm carried thereby, a pair of release levers coöperating with said trip arm to hold said stop mechanism inoperative, one of said release levers being actuated by the needle driving mechanism so as to release said trip arm when the needle is in the elevated position, a pivoted lever coöperating with the second of said release levers, and adapted 110 to be actuated by said carrier head at a predetermined position, whereby when said carrier head reaches said predetermined position the sewing machine is automatically stopped and the needle retained in the elevated position, all coacting substantially as described for the purpose specified.

2. In a special work sewing machine, the combination of a carrier head adapted to travel in a quadrangular path, a trip pin 120 carried by said carrier head, a work holder carried by said carrier head adapted to travel in a quadrangular path, an automatic stop mechanism for said sewing machine, a trip finger for actuating the same, a release 125 lever normally engaging said trip finger for holding said automatic stop mechanism inoperative, a pin having connection with said release lever disposed in the path of the trip pin on the said carrier head to be actuated 130

- by said trip pin in passing, whereby said release lever is moved to release the said trip finger at a predetermined position of said carrier head, as described.
- 5 3. In a special work sewing machine, the combination of a suitable guide base, a carrier head guided thereon, an arm projecting from said carrier head, a spring pressed arm carried by said last named arm, a work holder carried thereby, an upwardly projecting hook on said arm, an elevator hook yieldingly pivoted in place, and disposed to engage the said hook on the work holder arm when the work holder reaches a predetermined position, means for actuating said elevator hook, an automatic means for stopping the sewing machine when said work holder reaches said predetermined position, all coacting substantially as described and 20 for the purpose specified.
4. In a special work sewing machine, the combination of automatic stop mechanism, having a rock shaft, a finger carried by said rock shaft, a work holder, means for lifting 25 said work holder, an interlocking plunger adapted to engage the work holder lifting means, and disposed to be actuated into engaging position by the finger on said rock shaft when the automatic stop mechanism is 30 actuated to release the machine to permit its operation, and spring means holding said plunger normally disengaged, all coacting
- substantially as described and for the purpose specified.
5. In a special work sewing machine for 35 the attachment of labels or the like, the combination of an automatic stop mechanism having a rock shaft, a finger carried by said rock shaft, a work holder, means for lifting said work holder, an interlocking plunger 40 adapted to engage the work holder lifting means, and disposed to be actuated by the finger on said rock shaft into engaging position when the automatic stop mechanism is actuated to release the machine to permit its 45 operation, all coacting substantially as described for the purpose specified.
6. In a special work sewing machine, the combination of an automatic stop mechanism, a work holder, means for releasing 50 said work holder, and an interlock for preventing the operation of said work holder release, connected to be controlled by the automatic stop mechanism, all coacting substantially as described for the purpose specified. 55

In witness whereof, I have hereunto set my hand and seal in the presence of two witnesses.

ARTHUR ROSENTHAL. [L. S.]
